(57) **CLAIM**

I claim the ornamental design for a jeans with clasps, as shown and described.

DESCRIPTION

FIG. 1 is a front perspective view of jeans with clasps;

FIG. 2 is a front view of FIG. 1;

FIG. 3 is a rear view of FIG. 1; and,

FIG. 4 is a side view of FIG. 1.

The broken lines showing a clasp feature in FIGS. 1-3 represent the portions of the design, which form no part of the claim. The remaining broken lines on the surface of the jeans represent stitching.
